SHIPPING AND DISPLAY PACKAGE

Benjamin Klein, Long Island City, N. Y., assignor
of one-third to Erwin Richard Mihm and one-
third to Roy Herman, both of New York, N. Y.

Application January 12, 1937, Serial No. 120,169

3 Claims. (Cl. 206—44)

This invention relates to a carton of the type intended to be used for display of the goods shipped therein, and more particularly relates to such a carton designed to be self-advertising of the goods displayed.

An object of the invention is to provide a carton of the knock-down type which can be fabricated in the initial form of individual one-piece blanks and sold in quantity to manufacturers, the blanks being stacked in the flat, and each blank being adapted to be printed in the usual manner, with legends descriptive of the goods, the conventional usage being to erect the carton to the extent necessary to receive the goods, and then to close-in the goods for shipment, by means of a hinged lid, but without special provision of means for effective presentation of leaflets or other advertising media.

Such literature is ordinarily enclosed loosely within the carton, or in the larger boxes in which the smaller units are shipped, and there is often a reluctance on the part of store managers and salesmen to exert any effort to make such a sales appeal effective by displaying it properly in juxtaposition with the goods, so that frequently the literature finds its way at once into the wastebasket. This tendency is aggravated by the real difficulty of making readily such a disposition of the literature that the sheets which contain it will not obstruct the goods and so prevent an inspection of the kind which aids in selling them to customers, such obstruction usually occurring when the pamphlets are laid upon the goods exposed for sale.

The alternative practice of laying the leaflets upon the store counter is in disfavor for the reason that a counter soon becomes cluttered with such advertising matter, interfering with proper display of the goods and detracting from the advertising value of the matter itself, as the general effect of a counter so used is untidy and unattractive to customers.

Under such conditions, a particular object of the invention is to provide a carton of the class described which comprises a container section and a cover section both fabricated as a unitary structure from suitable carton material, the cover section adjoining hingedly an edge of the container section and having a mouth arranged transversely of the cover and adapted to have tucked therein a bundle of leaflets, pamphlets or sheets printed with descriptive matter, these sheets being intended to accompany the carton when shipped with the goods therein, the cover section being erectable into a folded arrangement

whereby the goods in the container are uncovered for sale, and the descriptive sheets are extended upwardly and displayed in attention-arresting disposition, presented for ready removal at will by a prospective customer.

Another object of the invention is to provide a novel and compact package for shipment of goods, and which combines therewith, in a unitary assembly, an advertising display that can be set up without the need for any special skill or training on the part of the sales force, and which will be effective as a sales-aid throughout its life as a container for the goods to be sold.

Still another object is to provide a container having the above advantages, and comparing so favorably in cost with conventional containers which lack the display features, that the increased advertising value will more than pay for the added cost; and accordingly the carton may be thrown away when all of its contained articles have been sold.

Other objects and features of the invention will appear as the description of the particular physical embodiment of the invention selected for illustration progresses.

In the accompanying drawings like characters of reference are applied to corresponding parts throughout the several views which make up the drawings, in which:

Fig. 1 is a view in plan of a blank of suitable contour from which to fabricate a shipping and display carton, in the construction of which the present invention is embodied;

Fig. 2 is a view in perspective showing a stage in the formation of the carton in which the container part is fully erected and ready to be closed by the cover part;

Fig. 3 is a perspective view from a different angle, illustrating the manner of tucking in the cover after the container has received its contents for shipment;

Fig. 4 is a perspective view from the same angle, illustrating the loaded container with the cover fully closed and provided with a bundle of advertising pamphlets, as the assembly appears when ready for shipment;

Fig. 5 is a view in front perspective, illustrating an intermediate stage in the opening of the assembly, preparatory to arranging it for display;

Fig. 6 is a similar view showing the assembly fully arranged for display of its contents, with the advertising pamphlets presented for ready withdrawal.

In the now-preferred embodiment of the invention selected for illustration and description, the

reference character 11 designates generally a blank formed of suitable carton material, preferably of an attractive color and finish for display, and printed with suitable legends (not shown) descriptive of the goods to be shipped and displayed.

The lower part of the blank is of sufficient area, and suitably provided with lengthwise and transverse score lines, as 12-14 and 15-17; also slits 18, and tabs 19, to aid in the erection of a container part designated generally in Figs. 2 to 6 by the reference character 20, such container for shipment of any suitable articles being of known structure, that shown being merely illustrative in character, as any suitable form may be utilized.

In pursuance of the invention, provision is made of a cover section adapted to close in the top of the loaded container and also to serve as a support for the advertising matter to be displayed when the container is opened.

In the instance illustrated, this cover comprises an integral extension of the main portion 11 of the blank and is designated generally by the reference character 21, in Fig. 1. It adjoins the end-forming panel 22 of the container along the scored fold line 15 and its area is defined by scored longitudinal side lines 23, a front fold line 24, and a rear fold line 25 which is parallel with the edge fold 15 and constitutes the hinge around which the cover structure 21 swings bodily to the closed position shown in Fig. 4.

Before the cover is thus closed, the side wings 26 and the front flap 27 are bent down from their Fig. 5 position to their Fig. 3 position, so that they can be tucked in between the contents 30 of the container, and the contiguous inner side and front walls 28 and 29 thereof.

The cover section 21 (see Fig. 4), when swung down around the hinge 25, leaves within its rear portion a space which corresponds approximately in depth to the distance between fold lines 15 and 25, in pursuance of the invention, this space being intended to receive a bundle of advertising matter 33, so assembled with the filled carton that it is not likely to be displaced, either accidentally or by intention.

For this purpose, the cover section 21 is provided with an elongated slot 31, of suitable dimensions to permit ready introduction thereto slidingly of the bundle 33, so as to extend to the bottom of the carton, this mouth-like orifice being desirably provided with lip-like margins 32, as shown in Figs. 3 to 6, which lend themselves readily to digital manipulation when inserting the bundle 33, and at the same time present an attractive, ornamental appearance across the respective faces of the bundle, in the display position shown in Fig. 6.

The cover and bundle are designed and intended to be erected to this Fig. 6 display position without the need for removal of the bundle from its originally inserted position in the slot 31, and certain novel structural features have been provided with this end in view, as well as to render the entire "set-up" of the display one which will arrest the attention of a possible purchaser and direct it favorably to the goods and to the advertising matter in the bundle, which is intended to be removable at will, as indicated by a suitable legend, such as "Take a Leaflet".

In order to support the bundle of leaflets in their erect position, and to create an effect of stability or solidity at the same time, the cover section 21 is cut and scored across its medial portion 75 in such a manner as to provide the four short

fold lines 34, two at either end of the mouth 33, leaving a small web 35 at each side, these serving as abutments for the bundle, and also acting to connect the front wall 37 with the rear wall 36 of the pocket formed by the bending over and downward of that portion of the cover 21 which is constituted by the front wall or panel 37 and its adjoining front end flap 27.

It will be understood that the front flap 27 is tucked in front of the bundle of leaflets and in back of the contents 30 of the container 11 (see Fig. 6) when the display is set up, and as the contents are removed from front to rear progressively, the erect display position will be maintained until all of the articles exposed in the 15 container 11 shall have been sold.

Any number of leaflets found desirable may be included in the bundle 33, and the removal of any of the number so included will not diminish the effectiveness of the display, as the legend 20 "Take-a-Leaflet" may be a relatively inconspicuous part of the matter printed on the face of the panel 37, and the absence of any leaflets will be likely to provoke an inquiry for information.

As long as any of the articles intended to be 25 sold remain at the rear of the container 11, the erect position of the folded-over panels 36 and 37 will be maintained, regardless of the presence or absence of leaflets, and the attractiveness of the display will continue. This may be enhanced by 30 pinking the edges of the wings 26, as illustrated, or by any suitable ornamentation thereof.

When all of the articles in the container have been sold, it may be thrown away, and a new carton opened up to display a fresh supply of the 35 goods, as the expended package has performed its intended function, and the difference in expense of fabrication and of material, as compared with a carton of like structure, but of conventional form, without the display features, is more than 40 paid for by the advertising value of the display, and by the elimination of waste due to the first-mentioned tendency of clerks and shopkeepers to throw away leaflets when the latter are only available in a loose form which results in littering up 45 the store counters.

From the foregoing description, it will be evident that the invention provides a compact and novel package for shipment of goods, and which combines therewith, in a unitary assembly, an 50 advertising display that can be set up without the need for special skill or training on the part of the sales-force, and which is effective as a sales-aid throughout its life as a container for the articles to be sold.

While I have disclosed the best physical embodiment of the invention known to me at the present time, it is to be understood that the form shown is merely illustrative and does not exhaust the 60 possible physical embodiments of the idea of means which underlies the present invention.

I claim:

1. As a new article of manufacture, a shipping carton in combination with a bundle of advertising media, said carton comprising a container section, and a cover section joined to an edge of the container section by an integral hinge strip defined by a double fold line, said cover having a transverse slot, and said bundle being tucked into said slot, overlying the forward part of the 70 cover and underlying the rear part thereof.

2. As a new article of manufacture, a shipping carton in combination with a bundle of advertising media, said carton comprising a container section, and a cover section joined to an edge of 75

the container section by an integral hinge strip defined by a double fold line, said cover having a transverse slot, and said bundle being tucked into said slot, overlying the forward part of the cover and underlying the rear part thereof and extending in front of the back portion of the container to the bottom thereof, the cover parts thus disposed being arranged in downwardly inclined position from rear to front, so that a mean average thickness for the package is thereby established, and said package is thereby adapted to occupy a level position when packed with a multiplicity of other packages.

3. A shipping and display carton of the class described, comprising a container section and a cover section, both fabricated as a unitary structure from suitable carton material, said cover sec-

tion adjoining hingedly an edge of said container section by a double fold line and having a pair of medial transversely disposed hinged connections separated by a mouth through which have been tucked a bundle of descriptive matter or sheets, said bundle occupying, in the erected position of the cover, its original position through said mouth, and retained therein by the front wall of the cover section, said front wall occupying a position folded down over and in front of the lower portion of the bundle, and the front flap of the cover being tucked behind the contents of the container near the rear thereof, and acting as an anchor for the cover, maintaining the erect position thereof for display.

BENJAMIN KLEIN.
